United States Patent Office

Des. 218,067
Patented July 14, 1970

218,067

EXTERIOR LAMP

Robert P. DeVito, Montreal, Quebec, Canada, assignor
to McElheron and DeVito Inc., Montreal, Quebec, Canada

Filed July 22, 1969, Ser. No. 18,334

Term of patent 14 years

Int. Cl. D26—03, 02

U.S. Cl. D48—31

Fig. 1

Fig. 2

Fig. 3

FIG. 1 is a perspective view of the exterior lamp according to the new design;

FIG. 2 is a side view thereof; and

FIG. 3 is a side view of the exterior lamp showing the roof in cross-section.

I claim:

The ornamental design for an exterior lamp, as shown.
